UNITED STATES PATENT OFFICE.

ALBERT B. ALLEN, OF CHICAGO, ILLINOIS, ASSIGNOR TO ALBERT C. CLARK,
OF CHICAGO, ILLINOIS.

INHALER.

No. 853,431.

Specification of Letters Patent.

Patented May 14, 1907.

Application filed October 12, 1903. Serial No. 176,867.

To all whom it may concern.:

Be it known that I, ALBERT B. ALLEN, a citizen of the United States, and a resident of Chicago, Cook county, Illinois, have invented 5 certain new and useful Improvements in Inhalers; and I do hereby declare that the following is a full, clear, and exact description of the same, reference being had to the accompanying drawings, and to the letters of reference marked thereon, which form a part of 10 this specification.

This invention relates to improvements in nasal inhalers of that class used for the administration of anesthetics and is shown 15 more particularly embodied in a form adapted for the use of dentists, surgeons and others who are required to operate upon the mouth and teeth or throat.

Heretofore in the inhalers of the class described 20 the mechanism conducting the vapor to the nostrils more or less covers the upper lip and portions of the mouth, rendering it difficult to perform surgical operations thereon or dental operations on the upper teeth. Furthermore 25 with most of the inhalers of the class described the bag containing the inhalant is usually supported at the side of the face and in many instances is in the way of the operator. In the case of a dental operation 30 the bag is sometimes so compressed by the arm of the dentist as to cut off the supply of the inhalant.

The object of this invention is to provide a nasal inhaler so constructed as to be readily sterilized, to permit the greatest freedom of 35 access to the mouth, throat or teeth of the patient by the operator, and, to provide a construction in which the inhalant is protected from dilution by mixture with atmospheric or the respired air. The inhaler is 40 adapted to retain its operative position independent of any movement of the patient enabling operations to be conducted as readily as in those in which anesthetics are not required.

The invention embraces many novel features and consists in the matters hereinafter described and more fully pointed out and defined in the appended claims.

In the drawings: Figure 1 is a view illustrating 50 the application of an inhaler embodying my invention. Fig. 2 is an enlarged vertical section through one of the nasal tubes and the respiratory valve. Fig. 3 is an

enlarged central vertical section. Fig. 4 is 55 an enlarged vertical section of a slightly modified form of my invention illustrating its application and use. Fig. 5 is a longitudinal section of the main pipe. Fig. 6 is an enlarged sectional detail of one of the nasal terminals or nozzles. Fig. 7 is a fragmentary longitudinal section of one of the nasal or inhalant tube illustrating the flexible connection thereof with the body of the inhaler.

In said drawings:—A indicates a flexible 65 tube of rubber or other suitable material shaped to fit transversely across the face just above the eyes and provided on each end with a cap a affording a tight closure therefor on which is secured a loop a' which affords means for attachment with the rubber or other elastic band a² adapted to be passed around the head of the patient and which binds the inhaler in position. Secured in one side of said tube A intermediate its ends, 70 and a distance apart sufficient to permit the same to lie along each side of the nose of the patient, are downwardly extending substantially parallel tubes B—B of metal, hard rubber or other suitable material which are 80 screw threaded at their upper ends and provided with a peripheral flange b below the threads which engages against the outer side of said tube so that when the nut b' is secured on the threaded inner end of said tube 85 said flange and nut positively engage the walls of said tube and afford a tight joint though permitting said tubes to be turned slightly for purposes of rotarial adjustment. At their lower ends said tubes are provided 90 with a somewhat abrupt inward and upward turn which extends immediately beneath and upwardly into the nostrils of the patient. Said upturned ends are each threaded to afford engagement with a nozzle B' which fits 95 closely in the nares of the patient and affords a closure therefor permitting inhalation only through said tubes B. As shown in Figs. 2, 4 and 6 said tips or nozzles for said tubes B may be made of metal or other rigid 100 material or of soft rubber or other resilient material, shaped for engagement on the inner ends of said pipes B and conical in form to fit the nares and each of the same as shown is provided near its base with a thin, peripheral resilient flange b² which engages below the nares and while permitting exhalation therefrom, serves as a valve to completely 105

close the nares to prevent inhalation of atmospheric air. Should the nozzles be of hard or rigid material as shown in Fig. 2 the same are provided with a peripheral groove 5 near the base in which is secured a disk of dam rubber or other resilient and impervious material. Opening outwardly from said tube A on the upper side thereof, are valves C each of which is positioned closely adjacent 10 to the inner end of one of said tubes B. Each of said valves comprises an apertured shell or cage c adapted to be secured in said tube and provided at its inner end with an inwardly directed flange c' below the apertures which affords a bearing for a thin resilient plate or diaphragm c² of mica or other suitable material which falls with each inspiration upon said flange tightly closing the valve and preventing admixture of atmospheric air with the inspiration. The expiration raises said diaphragms sufficiently to permit the respired air to pass freely therethrough. Secured centrally at the upper side of said tube A and opening thereinto is a 25 nipple D adapted for engagement with the anesthetic supply pipe D' connected in a gas bag d of any kind or construction, adapted to afford a supply of the inhalent to the patient. In inhaling devices of this class ordinarily 30 used, no provision is made to prevent admixture of expired air contaminated with organic matter from mixing with and diluting the inhalent gas contained in said bag d. For the purpose of preventing such admixture a perforated plate is provided transversely in said 35 nipples D affording an integral diaphragm wall at the center of which on the side adjacent the inhaler or tube A is attached a thin flexible diaphragm of resilient material such 40 as dam rubber or the like which acts to permit free flow of the inhalent from the bag into the inhaler but immediately closes the perforations in said diaphragm wall D² during the expiration and affords a very sensitive valve which prevents the expired air 45 passing to said gas bag should the pressure therein be such as otherwise to permit the same.

In the construction shown in Fig. 4, the 50 gas bag d' is suspended from the supply pipe D³ at a point below the head. In this arrangement the pipe D³ is made of any desired length and provided at its extremity with a fitting or nipple d⁴ screw threaded at its outer 55 end which has threaded engagement in the complementally threaded end of a casing D⁴ flanged at its opposite end to engage the tube A centrally affording a flexible connection therewith. Extending transversely across 60 the casing D⁴ is a diaphragm wall D⁵ similar in all respects with the diaphragm wall D² and likewise provided on its inner side with a resilient impervious sheet d⁶ which admits the gas freely through said valve but prevents 65 exhaled air passing into the bag.

The operation is as follows:—In use the pipe A rests transversely on the forehead close above the eyes and is bound in position by means of the bands a² which pass around the head of the patient. The inhalation 70 pipes B—B extend downwardly on said side of and close to the nose and the lower ends thereof inwardly and upwardly within the nares within which the nozzles or terminals fit closely with the resilient flange bearing 75 against and completely closing the same. The gas bag being now connected and supplied with the inhalent, inspiration closes the valves C and draws the gas through the valve in the supply pipe freely, also drawing 80 the resilient flange b³ inwardly completely excluding atmospheric air from the nares. Expiration produces the opposite results, closing the valve in the supply pipe, opening the valves C and also in some cases permitting 85 a part of the exhaled air to pass directly outward past the flanges b³.

Obviously the inhaler may be constructed of any desired material suitable to ready sterilization. Conveniently the pipe A may 90 be of flexible rubber and the inhalation pipes B of hard rubber or of metal, their connection with the rubber pipe A affording sufficient resiliency to permit ready adjustment. If preferred, however, the pipe A and inhalation 95 pipes B may all be of either metal or other rigid material in which event a flanged washer b⁵ of rubber or other yielding material is secured on the end of the pipes B and forced into suitable apertures in the pipe A, 100 affording a flexible joint adapted to permit ready adjustment.

Obviously many details of construction may be varied without departing from the principles of this invention.

I do not claim broadly the idea of the separate inhaling tubes communicating with a casing or receptacle or with a source of supply of inhalent, as the same is the invention of Albert C. Clark and made the subject of the latter's application for patent for improvement in inhalers filed October 14, 1903, Serial Number 176,952.

I claim as my invention:

1. A nasal inhaler comprising a flexible 115 casing and a pair of rigid inhaling tubes having swiveling connection therewith and adapted to be inserted in the patient's nostrils.
2. A nasal inhaler comprising a flexible 120 casing, and a pair of inhaling tubes which have at one end adjustable connections with the casing and whose other ends are adapted to be inserted in the patient's nostrils.
3. A nasal inhaler comprising a flexible 125 casing and a pair of inhaling tubes, whose inner ends are swiveled to the casing.
4. A nasal inhaler comprising a casing, a pair of inhaling tubes swiveled thereto at their inner ends, and an exhalation valve ar- 130

ranged in the casing adjacent the inner ends of the tubes.

5. A nasal inhaler comprising a casing formed of flexible material, a pair of rigid inhaling tubes having swiveling connection therewith at their inner ends, and an exhalation valve arranged in the casing adjacent the inner ends of the tubes.

6. An anesthetic inhaler comprising a tubular receptacle shaped to rest on the forehead, a supply pipe opening thereinto an inwardly opening valve in the connection, inhaler pipes adjustably engaged in said receptacle and adapted to lie close on each side the nose and shaped at their end to extend into and fit the nares, means adapted to secure the device to the head and an outwardly opening valve in the receptacle.

7. A nasal inhaler comprising inhaler pipes adapted to extend into and fit the nares and extending inwardly along the nose, a valved receptacle supported on the forehead and to which said pipes are swivelly connected and with which they communicate, and a valved supply pipe connected to the receptacle and extending over the head.

8. A nasal inhaler comprising a reservoir, rigid inhaler pipes connected thereto and adapted to lie on each side of the nose and bent to extend beneath and upwardly therein, a nozzle on each of said pipes adapted to loosely fit the nares and a resilient flange at the base of each affording a valve to close the nasal orifices during inspiration while permitting free expiration therefrom.

9. A nasal inhaler comprising a reservoir or receptacle, means adapted to secure the same upon the forehead, pipes flexibly connected in said receptacle and adapted to lie on each side of the nose and shaped to extend into the nares, nozzles on the pipes acting to exclude atmospheric air during inspiration, a source of inhalent supply connected in said receptacle, an inwardly opening valve in said connections, an outwardly opening valve in

said receptacle adjacent the ends of the inhaler pipes whereby free expiration is permitted without dilution or contamination of the inhalent fluid.

10. A nasal inhaler comprising a relatively large pipe bent to fit across the forehead, straps secured thereon adapted to secure the same to the head, inhaler pipes flexibly connected in said pipe and extending downwardly on each side of and in close relation with the nose and beneath the wings thereof and into the nares, means thereon adapted to close the nares to the admission of atmospheric air, outwardly opening valves in said pipe adapted to permit free expiration, a supply pipe connected in said pipe, a valve opening therefrom to admit the inhalent fluid to the inhaler, and a gas bag supported on said supply pipe and positioned to be out of the way of an operator.

11. An inhaler comprising a closed receptacle of soft rubber shaped to fit the forehead, attaching bands thereon adapted to bind the same to the head, inhaler pipes flexibly connected in said receptacle and positioned to extend closely beneath and into the nares, means thereon preventing inspiration of atmospheric air, outwardly opening valves in said receptacle, a supply pipe extending over the head of the wearer and connected to a gas bag, a valve opening into said inhaler from said supply pipe and acting to prevent contamination of the inhalent during expiration, the connection between said receptacle and inhaler pipes being such as to afford relative freedom of movement for purposes of adjustment.

In testimony whereof I have hereunto subscribed my name in the presence of two subscribing witnesses.
